WANTON S. WEBB, OF PROVIDENCE, RHODE ISLAND.

Letters Patent No. 87,228, dated February 23, 1869.

IMPROVEMENT IN ADVERTISING-DEVICES.

The Schedule referred to in these Letters Patent and making part of the same.

To all whom it may concern:

Be it known that I, WANTON S. WEBB, of the city and county of Providence, and State of Rhode Island, have invented a certain novel and useful Post-Office Letter-Distributer for Advertising-Purposes, &c.; and I do hereby declare the following specification, taken in connection with the drawings furnished, and forming a part of the same, to be a true and exact description of the same.

Figure 1 represents, in front elevation, one of my letter-distributers.

A represents a base, upon which the distributer rests, and is fastened, when in use, to a store-counter, or table.

B represents an archway of wood, fastened to the base A.

C represents an upright drum or cylinder, constructed so as to revolve upon pivots at the top and bottom.

D represents the base of the cylinder C, which projects through foot-piece of the arches B.

E represents, in each square on the cylinder C, a hook for holding letters by being compressed between it and the face of the cylinder.

Figure 2 represents the same in top section, the several parts being lettered as in fig. 1.

Figure 3 represents the cylinder C in vertical section, and is specially intended to show letter-boxes constructed at an angle with the face of the cylinder, to receive letters, when insufficient space is afforded for a full display of the same.

These boxes are marked C C.

In constructing these distributers for practical use, three sides would be closed, the same as is shown in the drawing upon the front side, having glass set into the arches, so as to give an unobstructed view of the cylinder C.

The entire surface of the cylinder, and of the outer case, save the glass, should be covered with advertisements, neatly set up to suit the size and form of the spaces to be occupied.

In practice, I would construct the cylinders with, say, twenty-six sides, one for each letter in the alphabet, and each side would be capable of displaying as many letters as the height of the cylinder would permit.

The distributer and advertiser is designed and intended for use in small, country post offices.

Let us suppose, by way of illustration, that one of my distributers were deposited in a country post office, gratuitously, for the use of the postmaster, and display of the advertisements upon it. If, as usual, the postmaster were store-keeper, he would place it near his desk, securely fastened to the counter. A mail, on being received, would be set up on the cylinder, each letter according to the alphabetical arrangement, covering one of the spaces occupied by a business-card.

Persons calling at the office or store, without disturbing the postmaster, can revolve the cylinder, by means of the protruding base D, and ascertain for themselves if any mail is for them.

The sides and front being closed, no access can be had to the cylinder, except from the rear of the counter.

These distributers should be neatly constructed, and of sufficient beauty to secure for them a ready reception by the postmasters, and to attract, not only the attention of persons calling for letters, but of all comers on other business.

To produce a post-office letter-distributer, of novel construction, and peculiarly adapted for general advertising-purposes, is the object of my invention.

I therefore claim as novel, and desire to secure by Letters Patent—

The post-office advertising-medium, consisting of the drum C, with the projecting flange D, protecting-guard B, arranged and operating substantially as shown and described, for the purposes specified.

WANTON S. WEBB.
